UNITED STATES PATENT OFFICE.

WINFIELD S. LIVENGOOD, OF KANSAS CITY, MISSOURI, ASSIGNOR TO ANDREW A. KRAMER, OF KANSAS CITY, MISSOURI.

EQUALIZING HOIST.

1,417,187.

Specification of Letters Patent. Patented May 23, 1922.

Application filed December 8, 1920. Serial No. 429,263.

To all whom it may concern:

Be it known that I, WINFIELD S. LIVENGOOD, a citizen of the United States, residing at Kansas City, in the county of Jackson 5 and State of Missouri, have invented certain new and useful Improvements in Equalizing Hoists; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to hoists for dump wagons and the like in which a winding drum and cables are used for raising one end of the vehicle body.

The invention contemplates the provision 20 of an equalizer whereby the strains will be distributed equally on the cables, there being two winding cables, one for each front corner of the dump body of the vehicle.

In the drawings,

25 Fig. 1 is a front, perspective view of a hoist mechanism and portion of the dump body.

Fig. 2 is an elevational view of the equalizer applied, part of the frame which supports it being shown in section, and

30 Fig. 3 is a top end view of the hoisting mechanism on which the equalizer is mounted.

The invention is illustrated as applied to 35 a hoisting mechanism such as is shown in my Patent No. 1,312,489 of August 5, 1919. The driving mechanism and cables are substantially like that shown in the patent, the essential difference being in the equalizer, 40 which is a material improvement over the construction shown in said patent.

1 designates a vehicle truck of any preferred construction having a chassis comprising side bars 2 and 3, on which may be 45 pivoted the dumping body 4, at the front corners of which are brackets 5 and 6, to the ends of which are fastened hoisting cables 7 and 8, which pass over the sheaves 9 and 10 on the upper ends of the hoisting frame 50 11. The cables also pass over the sheaves 12 and 13 of an equalizing device consisting of the sheaves and the supporting bars or levers 14 and 15, which are pivoted intermediate their ends, as at 16, to a shaft or 55 bolt 17, which passes through the side bars

18 and 19 of the frame 11. These side bars also support the sheaves 9 and 10.

The uprights or standards 20 and 21 of the frame 11 are carried by a channel 22, which constitutes the base for the frame, the 60 channel being resiliently secured to the side bars 2 and 3 by springs 23 and 24 in substantially the same manner as is shown in the said patent above referred to.

The hoisting mechanism consisting of the 65 drum 25 may be substantially like that shown in my former patent, the cables 7 and 8 being wound around the same so that when the drum is rotated in one direction, the dump body 4 will be raised and when the drum is 70 rotated in the opposite direction, the body will be lowered onto the chassis 1.

The essential feature of my invention in the present application is the equalizer, there being also novelty in the arrangement 75 of the equalizer with the peculiarly constructed frame shown.

If there is stretch in one of the cables, the equalizer frame consisting of the bars 14 and 15 will tilt so that one of the sheaves 12 or 80 13 will be raised and the other lowered so that the slack will be taken up in the stretched cable and an equal pull will result on both cables.

The slack take-up or equalizer is freely 85 movable on the bolt 17 so that its action will be automatic and so that it will operate to prevent all of the strain from the load being exerted upon one cable, thereby providing for more efficiency and ease in operation of 90 the hoisting mechanism.

What I claim and desire to secure by Letters-Patent is:

1. A hoisting mechanism comprising a vertical frame having sheaves at its upper 95 end, a winding drum carried by the frame, cables connected to the winding drum and passing over the sheaves in opposite directions, and an equalizer carried by the frame between the sheaves and consisting of pivoted bars and sheaves mounted between them.

2. A hoisting mechanism comprising a base, vertical bars supported on said base, plates fastened to the lower portions of the 105 vertical bars, top plates connecting the upper ends of the vertical bars, the ends of the top plates projecting beyond the vertical bars, sheaves between the projecting ends, a sheave frame pivoted intermediate its ends 110

between the top plates, sheaves at the ends of the plates, a drum mounted between the plates at the lower ends of the bars, cables on the drums passing between and over the 5 sheaves on the sheave frame and over the sheaves carried by the projecting ends of the top plates, and a dump body connected to the ends of the cables.

3. A hoisting mechanism comprising a 10 base, vertical bars carried by said base, top plates connecting the upper ends of said bars, the bars having in-bent and outwardly extending projecting ends to form sheave bearings, sheaves carried by the ends of the 15 bars, a frame pivoted between the plates and confined between the vertical bars, sheaves carried by the pivoted frame, a drum supporting means carried by the lower portions of the vertical bars, a winding drum carried 20 thereby, and cables on the drum passing be-

tween the sheaves on the pivoted frame and over the sheaves carried by the ends of the top plates, the free ends of the cables being adapted to be secured to the load to be raised.

25

4. A hoist comprising a base, vertical bars supported by said base, transverse plates connecting the upper ends of said bars and having ends extending beyond them, sheaves carried by the extended ends 30 of said plates, a bolt projecting through said plates, a pair of plates pivotally supported on said bolts and between the first named plates, the last named plates being confined between the first named plates and the vertical 35 bars, and sheaves carried by the ends of the second mentioned plates.

In testimony whereof I affix my signature.

WINFIELD S. LIVENGOOD.
